MINIATURE PHOSPHORESCENT TABLE LAMP

Irving Hartley Steinhardt, New York, N. Y.

Application October 1, 1949, Serial No. 5,246

Term of patent 14 years

(Cl. D48—20)

To all whom it may concern:

Be it known that I, Irving Hartley Steinhardt, a citizen of the United States, residing at New York, in the county of New York and State of New York, have invented a new, original, and ornamental Design for a Miniature Phosphorescent Table Lamp, of which the following is a specification reference being had to the accompanying drawing, forming part thereof.

In the drawing

Fig. 1 is a side view in elevation of a miniature phosphorescent table lamp, showing my new design;

Fig. 2 is a top plan view thereof.

I claim:

The ornamental design for a miniature phosphorescent table lamp, substantially as shown.
IRVING HARTLEY STEINHARDT.
